DESIGN FOR AN UPHOLSTERY NAIL

Louis LeBreux, Waterbury, Conn., assignor to
The Beardsley & Wolcott Manufacturing Com-
pany, Waterbury, Conn., a corporation of Con-
necticut

Application June 22, 1936, Serial No. 63,424

Term of patent 14 years

To all whom it may concern:

Be it known that I, Louis LeBreux, a citizen of Canada, and residing at Waterbury in the county of New Haven and State of Connecticut, have invented a new, original, and ornamental Design for Upholstery Nails, of which the following is a specification, reference being had to the accompanying drawing, forming part thereof.

Fig. 1 is a top plan view of the upholstery nail, showing my new design.

Fig. 2 is a side view of the same.

Fig. 3 is a longitudinal sectional view of the same, showing the ornamental configuration of the nail.

The characteristic features of my design are the beads of irregular closed loop-shaped form raised above the enclosed and surrounding depressed flat smooth areas, resembling the appearance of turtle-spots, the beveled lower rim of the upholstery nail head and the sharp contrast in light and shade effects between the raised looped beads and smooth base of the head.

I claim:

The ornamental design for an upholstery nail as shown and described.

LOUIS LEBREUX.
